UNITED STATES PATENT OFFICE.

FRED C. KELLER AND CHARLES E. OATHOUT, OF CLEVELAND, OHIO, ASSIGNORS TO
K. & E. BLOUSE MAKERS, A FIRM COMPOSED OF E. K. HAYS, LOUIS H. HAYS, AND
G. P. WAITZFELDER, OF CLEVELAND, OHIO.

DESIGN FOR A GARMENT.

46,167.

Specification for Design.

Patented July 28, 1914.

Application filed May 1, 1914. Serial No. 835,766. Term of patent 14 years.

To all whom it may concern:

Be it known that we, FRED C. KELLER and CHARLES E. OATHOUT, citizens of the United States, and residents of Cleveland, county of Cuyahoga, State of Ohio, have jointly invented a new, original, and ornamental Design for Garments, of which the following is a specification, reference being had to the accompanying drawing, forming part thereof.

The figure is a perspective view of a garment showing our new design.

We claim:—

The ornamental design for a garment as shown.

FRED C. KELLER.

CHARLES E. OATHOUT.

Witnesses:

LOUIS H. HAYS,

F. E. BODEN.
